UNITED STATES PATENT OFFICE.

WALTER C. CARLSON, OF MILWAUKEE, WISCONSIN.

ADVERTISING DISPLAY CONTAINER.

Application filed May 3, 1923. Serial No. 636,328.

To all whom it may concern:

Be it known that I, WALTER C. CARLSON, citizen of the United States, residing at Milwaukee, county of Milwaukee, and State 5 of Wisconsin, have invented new and useful Improvements in Advertising Display Containers, of which the following is a specification.

My invention relates to improvements in 10 advertising display containers, with particular reference to containers for confections and other small articles to be attractively displayed.

The object of my invention is to provide a 15 form of container which may be supported in an inclined position to display the contents, and in which the cover may also be supported in a raised position to display attractive contours associated with artistic 20 or advertising matter, printed, lithographed, or embossed thereon or applied thereto.

More specifically stated, my object is to provide improved supporting means, associated with the bottom of the container, and 25 adapted to be adjusted in either a folded or unfolded position to allow the container to be shipped or stored with the bottom in a horizontal position and the supporting means folded, or to be set up for display 30 with the supporting means unfolded and the container in an inclined position; also to provide means whereby, when the container is supported in an inclined position, the lid may be supported from the back wall of the 35 container with adequate stability and in a position to display artistic designs or advertising matter thereon to the best advantage; also to provide an improved knock-down container having integrally connected 40 walls, an integrally connected support of the character above described, and an integrally connected cover member or lid, all adapted to be folded and adjusted in position for use as a container by the manufacturer of confections, and further adjusted 45 for display purposes by the dealer.

A further object of my invention is to provide an improved form of cover or lid for containers of the described class, where- 50 by when the lid is raised it may be folded or adjusted in such a manner as to display contours wholly dissimilar from those of an ordinary lid and characteristic of the

artistic or advertising matter to be displayed. 55

In the drawings:

Figure 1 is a front elevation of the container embodying my invention as it appears when adjusted in display position.

Figure 2 is a side elevation of the same. 60

Figure 3 is a plan view with the lid raised, with dotted lines indicating the support underneath the container.

Figure 4 is a rear elevation.

Figure 5 is a sectional view drawn to a 65 plane on line 5—5 of Figure 3, with the display portion of the cover partially broken away.

Figure 6 is a plan view of the box with 70 the lid in closed position.

Figure 7 is a view of the container in knock-down form, as it is when prepared for shipment from the box manufacturer to the manufacturer of confections.

Figure 8 is a fragmentary sectional view 75 on line 8—8 of Figure 5.

Like parts are identified by the same reference characters throughout the several views.

My improved container is provided with 80 a bottom wall 1, end walls 2, front or side wall 3, back or side wall 4, and marginal top wall portions 5 and 5'. A portion of the top wall is partially cut away to form a lid comprising portions 6 and 7 partially 85 severed or separated by a slit 8 of peculiar contour, as hereinafter explained. At the ends of the slit 8 crease lines 9 extend to the side margins of the lid portion. The central portion of the front margin of the 90 lid is provided with a lip 10 which may extend to the front wall 3, this lip being cut from the marginal top wall portion 5'.

The lid is in crease joint connection with the back or side wall 4 along the line 15, 95 whereby the lid may be raised as if hinged to the back wall. When so raised the portion 7 may be folded downwardly and inwardly about the axis formed by the crease lines 9, and the lip 10 may then be inserted 100 through slits 16 and 17 formed in the back wall 4, whereby the lip passes back of a retaining bar 18 partially cut from the back wall by said slits. The down turned portion 105 7 of the lid is thus securely anchored by the lip 10 to the back wall, the lip 10 co-operat-

ing with the crease hinge connection at 15 to support the folded lid in a raised position. It may be thus supported in a vertical position or in a position somewhat inclined 5 in either direction from the vertical position, the exact position being dependent upon the lip 10 and its engagement back of the bar 18, the friction being sufficient to hold it in the position in which it is adjusted. It is shown by dotted lines in Figure 2 in a backwardly inclined position. The parts being composed of cardboard, it is obvious that the lip 10 may be bent or flexed to suit the requirements for holding 10 the lid in the desired position.

By offsetting the contour lines 8 from the folding crease lines 9 of the lid, it is obvious that when the lid is folded the offset portion between the crease lines 9 and the 20 contour slit 8 will be exposed in a raised position, as indicated in Figure 1, and the contour line 8 may thus be utilized in connection with pictorial illustrations such as the illustration 20 (Figure 1) to produce realistic impressions that could not be obtained by pictorial illustrations alone.

In the construction shown, the contour slit 8 is offset from the crease lines 9 into the portion 6, whereby, when the portion 7 is 30 swung downwardly and secured to the back wall by means of the lip 10, the portion containing the pictorial illustration 20 will swing upwardly to a position where it will be projected above both of the lid portions 6 and 7, thus attracting attention by reason of its upwardly projected or isolated location, its peculiar contour, and the pictorial illustration which it carries.

It will be observed in Figure 7 that my 40 improved box can be formed from a blank comprising a single piece of cardboard, cut, slitted, and creased, as shown in Figure 7. These flat blanks so cut, slitted, and creased by the manufacturer, may be packed in superposed relation within suitable containers and shipped to the confectioner. As so 45 shipped, each blank, will of course, contain the desired pictorial illustrations and any desired printed matter, whereby, when the 50 confectioner receives them, he can readily fold or assemble each blank to form a container provided with the brace portion or support and with the lid in either the raised display position or in any other desired position. The box may then be filled with confectionery or other material and placed on display with the lid in the raised or folded 55 position in which it is illustrated in Figures 1 and 2.

60 The brace or supporting member, adapted for adjustment to support the box in an inclined position, is preferably formed inte-

grally with the front wall, to the lower margin of which it is connected at the crease line 22. Oblique crease lines 23 and 24 extend outwardly and convergently in the bracing portion to form a base 25 and triangular walls 26 and 27 adapted to be folded upwardly and inwardly, as best shown in Figures 4 and 5. Flaps 28 and 29 on the outer side margin of the wall portions 26 and 27 are connected with the portions 27 along the crease lines 30 and 31 respectively, and when the wall portions 26 and 27 are swung inwardly to box supporting position, these flaps may also be swung inwardly from the upper margins 30 and 31 of the portions 26 and 27 and interlocked with each other by engaging the lip 32 of one of these flaps in a slit 33 formed in the other one, as best illustrated in Figure 3. The end walls 2 are preferably formed integrally with the top and connected with the marginal portions 5 of the top at the crease lines 35. These end wall members 2 are provided with flaps 37 adapted to be folded inwardly upon the upper surface of the bottom 1. At the ends, notches 39 are provided, whereby corner flaps 40 and 41 connected with the front and back or side walls 3 and 4, respectively, 90 may be swung inwardly to an interlocking position, as best shown in Figure 8. The ends of the flaps 37 may, if desired, be slightly upturned, as shown in Figure 7, to secure a more effective interlocking engagement of the corner flaps in the notches 39 when the box is assembled in condition for use as a container.

It will, of course, be understood that the brace portion or support for the box, composed of the members 25, 26, 27, 28, and 29, will be swung underneath the bottom 1 when the parts are being assembled, and adjusted for use as a support.

I claim:

In a box having a top provided with side walls integrally connected therewith and a bottom integrally connected with one of said side walls, a base for supporting said box in an inclined position and foldable underneath the bottom, said base comprising a portion integrally connected with the other of said side walls and having substantially parallel crease lines extending outwardly from corresponding ends of the last mentioned wall, and inwardly converging crease lines each extending from a point on one of said first mentioned crease lines adjacent the last mentioned wall, flaps upon opposite sides of said portion integrally connected therewith and having means for interlocking said flaps.

WALTER C. CARLSON.
